(57) **CLAIM**

The ornamental design for panel sections for an air handler door, as shown and described.

DESCRIPTION

FIG. 1 is a front view of a first panel section for an air handler door showing our new design;

FIG. 2 is a top view of the first panel section of FIG. 1;

FIG. 3 is a side view of the first panel section of FIG. 1;

FIG. 4 is a rear view of the first panel section of FIG. 1;

FIG. 5 is a bottom view of the first panel section of FIG. 1;

FIG. 6 is a front view of a second panel section for an air handler door showing our new design;

FIG. 7 is a top view of the second panel section of FIG. 6;

FIG. 8 is a side view of the second panel section of FIG. 6;

FIG. 9 is a rear view of the second panel section of FIG. 6; and,

FIG. 10 is a bottom view of the second panel section of FIG. 6.

The broken lines in FIGS. 1, 4, 6, and 9 are included for purpose of illustrating only and form no part of the claimed design.
